UNITED STATES PATENT OFFICE

FRANZ P. SCHNEIDER, OF CHICAGO, ILLINOIS, ASSIGNOR TO TRANSO ENVELOPE COMPANY, OF CHICAGO, ILLINOIS, A CORPORATION OF DELAWARE

GUIDE CARD

Application filed June 9, 1928. Serial No. 284,057.

The present invention relates more particularly to a guide card for indicating the proper position for address, place to fold and/or for arranging printed or analogous matter on forms and letters that are to be placed and mailed in window envelopes.

The use of window envelopes has grown to such an extent they are now used exclusively in many of the largest industries and 10 a great many different sizes are used. In the use of these window envelopes the Post Office Department has issued instructions to the effect that they object to matter other than the address showing through the window. 15 That is, in the interest of efficiency and to avoid confusion and mistake, the Post Office Department has ruled that nothing shall be visible through the window of the window envelope except the name of the addressee, 20 the address which may include the street address or post office box and city and State.

To comply with this post office ruling care must be exercised in applying the address to, or folding, the letter or other form that it 25 will be rightly placed when the sheet or form is folded to exhibit through the window only the address. Where a user utilizes a large quantity of window envelopes of different sizes it will be appreciated that a great amount 30 of skill and concentration is required in order that the address will be properly placed on the sheet or form for each of the different sizes of window envelopes, and that such form will be folded at the proper place.

I have given considerable thought to the problem of devising a means whereby the printed or analogous matter on forms to be placed in window envelopes can be accurately 40 arranged on the form so that only the desired printed matter will be visible through the window, which device will be applicable to the arranging of this printed matter correctly for all of the different sizes of window envelopes, or at least those sizes most frequently used, which means could also be utilized to indicate the proper place to fold.

As a result I have devised a guide card for indicating the proper and exact position for the address, the proper place to fold and/or 45 for arranging said printed or analogous mat-

ter correctly and accurately, regardless of the size of the envelope in which it is to be placed.

The utility of the invention as well as objects and advantages will be hereinafter made apparent.

In the drawings, Fig. 1 is a plan view of the guide card of the present invention.

Fig. 2 is a cross sectional view taken on line 2-2 of Fig. 1.

Fig. 3 illustrates the application of the 60 guide card to a form to be placed in an envelope of a predetermined size.

Fig. 4 is a plan view of a letterhead illustrating a series of dots placed thereon to indicate proper position for the address while 65 the guide card was being applied to the sheet illustrated in Fig. 3.

Fig. 5 illustrates a blank form showing in skeleton form the opposite ends of the window.

Fig. 6 is a plan view of a window envelope with the address printed on the form visible through the window, and no other data being visible.

Referring more in detail to the drawings, 1 75 designates a relatively stiff card blank taking the form generally of a rectangle having the sides 2, 3, 4 and 5. Adjacent the upper edge 2 and opening toward the edge 5 the card may be provided with a series of spaced right angle notches forming edges 6, 7, 8 and 9 parallel with the upper edge 2. Below each of the edges 6, 7, 8 and 9 the card carries identifying data 10 with an arrow indicating the size for which any of the edges 2, 6, 7, 8 80 and 9 may be used. The lower edge 4 is also provided with an inwardly cut away right angle notch opening to the edge 5 forming an edge 11 parallel with the edge 4.

Intermediate its edges the card may be provided with one or more cut outs 12 which may be curved on their outer edges to simulate in form the curved semi-rounded ends of a window in a window envelope. Adjacent the inner edges of the cut outs 12 the card may have imposed on its surface spaced short lines 13.

In the utilization of the guide card, first decide what size envelope it is desired to use. The guide is then placed in the upper left 100

corner of the form so that the notch indicated by the size of envelope desired is flush with the top of the form, while at the same time the left edge 5 of the guide is flush with the left edge of the form. Then a pencil may be drawn lightly around the curves of cut outs 12 to form curved outlines 16 and along the bottom edge of the guide that is indicated by the size of envelope desired, that is, if envelopes of size 9 and 10 for instance, are used, a line 14 can be drawn with the edge 4 as a guide, whereas, if envelopes of a size $6\frac{1}{4}$, $6\frac{3}{4}$, 7, $7\frac{1}{2}$ and 8 are used, the line 14 can be drawn with the edge 11 as a guide, the lines 14 in either case being the line of fold of the form suitable for the respective groups of the sizes of envelopes. The short lines 13 indicate the proper position for the address, there being three spaced dashes shown, the top one being 20 for the name of the addressee, the middle one being for the street address, post office box or other information, while the lower line is for the designation of the city and State. In place of outlining the cut outs 12, if the form 25 is being arranged for a typewriter, three small dots 13' may be printed on the form in the exact position indicated by the lines 13.

The use of the device should be apparent from the foregoing description and the illustration in the drawings. Assume, for example, that it is desired to typewrite the name, sheet address and city and State on the letterhead shown in Fig. 4. Assume further that it is desired to place this letter in size 35 10 envelope. The guide is placed in the upper left corner of the letterhead with the edge 2 flush with the upper edge of the letterhead and the edge 5 flush with the left hand side edge of the letterhead, as illustrated in Fig. 3. Dots 13' are then made, for instance, by a pencil opposite the lines 13 in the space allowed by the cut outs 12, and a short dash or dot made along the edge 4, after which the form is removed. The letterhead is then 40 inserted in the typewriter and the address placed in the proper position indicated by the dots 13'. Upon removal from the typewriter the letterhead is folded along the line 14, the balance of the letter being folded in 45 such a manner so that, when it is placed in the envelope illustrated in Fig. 6, only the address corresponding to the dots 13' will be visible through the window 15.

If the letter is to be placed in an envelope 50 of a different size, as heretofore described, the guide is placed in the upper left corner so that the notch or edge indicated by the size of envelope desired is flush with the top of the form and the left edge 5 of the guide 55 is flush with the left edge of the form.

The guide card of the present invention is also of utility in the printing of letterheads. In order that the letterhead (such as illustrated at 17 in Fig. 4) may be so placed on a form that it will not run into the address, a

blank sheet of the same size as the sheet on which the letterhead is to be printed is taken and the guide card placed thereon, as illustrated in Fig. 3, first having predetermined the size of the envelope in which the sheet is to be placed. With a pencil or the like, the ends of the window as indicated by the cut outs 12 is marked on the blank sheet, as illustrated in Fig. 5 at 16. The printer in arranging the letterhead takes this form and arranges all of the matter going into the heading in such a manner that it does not conflict in any way and comes outside of the area defined by the curved window simulating marks 16. After he has once arranged his data on the sheet so that it will not conflict and his form is set up, the letterheads can be printed and at no time will there be any portion of the letterhead exposed through the window 15.

Where a machine is used which simultaneously prints the addressee's name, street address and city, it may be necessary only to use the guide card on the first form, after which the machine, by manipulation, may be arranged so that the printing is done in exactly the right places.

While I have illustrated the guide card as provided with two spaced notches 12 simulating the opposite curved ends of a window envelope, it is to be understood that the cut outs 12 might be continued inwardly until they meet, or, in other words, the card may be entirely cut out to present a cut out of the exact size and contour of the window 15.

It is to be also understood that while I have illustrated the upper edge of the card as provided with four notches and the lower edge with one notch, and also while I have illustrated the sizes most used, that the guide card of the present invention is universal in its use from the smallest size of window envelope used to the largest. The upper edge 2 may be provided with any number of notches and corresponding data 10, and the same is true with the lower edge.

I claim as my invention:

1. A guide card for the purpose described, comprising a flat substantially rectangular blank having one corner cut away to form a series of right angular steps whose alternate edges are parallel to the adjacent side edges of the card respectively, and having a cutout within the body of the card for indicating the position of a window to be placed on a window envelope, the position of the cutout with respect to the right angular steps on one corner being similar to and defining the position of the window relative to the edge of the envelope.

2. A guide card for the purpose described, comprising a flat substantially rectangular blank having one corner cut away to form a series of right angular steps whose alternate edges are parallel to the adjacent side edges of the card respectively, and having a cutout

within the body of the card for indicating the position of a window to be placed on a window envelope, the position of the cutout with respect to the right angular steps on one corner being similar to and defining the position of the window relative to the edge of the envelope, there being a mark carried by said card adjacent said cutout for indicating the correct position for printed matter.

10 In testimony whereof I affix my signature.

FRANZ P. SCHNEIDER.
